Patented Oct. 31, 1916.

Fig. 1.

UNITED STATES PATENT OFFICE.

JOHN G. SEELIG, OF RIPON, WISCONSIN.

WASHING-MACHINE.

1,202,903.

Specification of Letters Patent. Patented Oct. 31, 1916.

Application filed October 22, 1915. Serial No. 57,221.

To all whom it may concern:

Be it known that I, JOHN G. SEELIG, a citizen of the United States, and resident of Ripon, in the county of Fond du Lac and State of Wisconsin, have invented new and useful Improvements in Washing-Machines, of which the following is a description, reference being had to the accompanying drawings, which are a part of this specification.

10 The invention relates to washing machines.

The invention is designed more particularly to provide a washing machine in which the agitating elements are a pair of pounders vertically reciprocable within the wash tub and so spaced from each other and from the sides of the tub as to efficiently accomplish the washing operation without the use 20 of any mechanism for revolving or oscillating them.

The invention further designs to provide a washing machine in which a pair of pounders are alternately vertically reciprocated and so disposed with respect to each other and the walls of the tub that the clothes will always come in contact with them while they move up and down within the tub.

30 The invention is further designed to provide a pair of pounders and mechanism for alternately vertically reciprocating said pounders, which mechanism consists of parts located on the lid of the machine, there being an absence of gears on that part 35 of the mechanism located on the lid which makes the machine very quiet.

The invention is further designed to provide a washing machine with two alternately vertically reciprocating pounders whereby there will be twice the agitation than in a one pounder type with the same speed of the operating handle, the two pounders will counter-balance each other 45 and thus make the machine easier to operate.

The invention is further designed to provide a new and improved form of washing machine.

The invention consists in several features 50 hereinafter set forth and more particularly defined by claims at the conclusion hereof.

In the drawing: Figure 1 is a plan view of the device embodying the invention, parts being broken away and parts being shown 55 in section; Fig. 2 is a section taken on the

line 2—2 of Fig. 1; Fig. 3 is a section taken on the line 3—3 of Fig. 1.

The device comprises a long and narrow tub 10 provided with a supporting frame work 11 and having an open top for which 60 a cover 12 is provided, agitating means carried by the cover and adapted to be disposed within the tub, and mechanism for operating said agitating means.

The rectangular cover 12 fits within and 65 is hinged to the upper open rectangular top 13 of the frame by hinges 14 and 15. The pintle or shaft 16 of the hinge 15 projects outwardly therefrom and serves as a stud shaft for a driving gear wheel 17 which is 70 mounted on its outer end. The pintle 16 is also journaled in a bearing bracket 18 which is bolted to the top of the frame and is provided with a downwardly extending side portion 18' having a horizontally projecting stud shaft 20 upon which a fly wheel 19 is journaled. A pinion 21 journaled on the stud shaft 20 and forming part of or turning with the fly wheel 19 meshes with the gear 17 and is driven thereby. The 80 cover 12 is provided with a combined latch and handle 12' for convenience in lifting the cover and for securing it in closed position.

It will be noted that the hinge 14 is in 85 axial alinement with the hinge 15 and the bearing of the bracket 18, the hinge 15 turning on the shaft 16 as its pintle, so that when the cover with its mechanism is raised, the shaft 16 will be partly turned but the fly wheel will not be lifted as it is mounted on 90 the frame of the machine.

A bracket 22 mounted on the top corner 95 adjacent the pintle 16 has an arm 23 extending outwardly and downwardly and carrying a stud shaft 24. A three arm bell crank lever 25 is fulcrumed on the shaft 24 and the inner end 26 of this lever is pivotally connected to one end of a link 27 which is pivotally connected at its other end to a wrist-pin 28 projecting from the driving gear 17. The outwardly and upwardly extending arms 29 and 29' are of tubular socket form to receive the end of the operating hand lever 30 which may be used in connection with either of said arms.

105 The agitating means comprises a pair of pounders 31 of any desirable form for engaging the clothes within the tub, mounted on vertically disposed shafts 32 which are slidably mounted within the cover 12 and in 110

a longitudinally extending bearing bracket 33 mounted on the central portion of the top of said cover. As previously pointed out, the tub 10 is long and narrow and the 5 pounds 31 are so disposed with respect to each other and to the walls of the tub that the clothes will always come in contact with them while they move up and down within the tub and so that they may efficiently accomplish the washing operation without the 10 use of any mechanism for revolving or oscillating them.

Means are provided for guiding each of 15 said shafts 32 and consists of a guide member 34 mounted on the end of each shaft 32 and provided with apertured extensions 35 and upright guide rods 36 mounted on the ends of the bracket 33 are slidably disposed within the aperture 37 of the extensions 35 20 whereby each shaft 32 will have a straight up and down movement within the cover and tub.

The mechanism for operating the agitating means comprises mechanism for alternately vertically reciprocating the pounder shafts 32. This comprises means for continuously rotating the pintle 16 and means operatively connected to the shaft or pintle 16 for alternately vertically reciprocating 30 the shafts 32.

The means for continuously rotating the shaft 16 consists of the lever 25, link 27^a, wrist pin 28 and gear 17. The oscillation of the lever, through the oscillation of the 35 operating handle 30, will, through the connections just described, continuously rotate the shaft 16.

The means operatively connected to the shaft 16 for alternately vertically reciprocating the shafts 32 comprises a crank 38 mounted on the inner end of the shaft 16, a link 39 pivotally connected at one end to said crank and pivotally connected at its other end to a crank 40 mounted on a shaft 41 journaled in the forked arms 42 of the bracket 33, a connecting member 43 mounted intermediate its ends upon said shaft 41 and provided with oppositely disposed arms 44 having bores 45 therein, and means for connecting said member 43 to the shafts 32. This means comprises plungers 46, the stems 47 of which are slidably mounted in the bores 45 and the forked heads 48 of which are pivotally secured to the shafts 32 by pins 49 50 passing through them and through the members 34 secured to the shafts 32. The continuous rotation of the shaft 16 will, through the crank 38, link 39, crank 40, shaft 41, member 43, plungers 46 and members 34 55 alternately vertically reciprocate the member 34 on the guide rods 36 and consequently alternately move the shaft 32 and pounders 60

31 up and down to accomplish the washing operation.

If it is desired to drive the mechanism by power it is only necessary to run a belt 65 around the fly wheel from the source of motion and drive in the ordinary manner.

It will be noted that the operative connection of the two pounders with the oscillating 70 shaft 41 for alternate reciprocation produces a well-balanced construction which makes the machine easier to operate than those of the single pounder type.

The invention thus exemplifies a washing 75 machine in which the washing operation is accomplished by a pair of alternately vertically reciprocated pounders.

I am aware that numerous changes may be made in practicing my invention by those 80 who are skilled in the art without departing from the scope thereof expressed in the claims. I do not wish, therefore, to be limited, unless necessary to the constructions I have shown and described.

What I claim as my invention is:—

1. In a washing machine, the combination, with a tub provided with a cover, of an oscillatory shaft mounted on the cover, a member carried by said shaft and provided 90 with arms extending on opposite sides of said shaft and having bores therein, plungers slidably mounted within said bores, pounder shafts vertically slidably mounted in said cover and pivotally connected to said 95 plungers, vertical guide rods carried by said cover, guide members carried by said pounder shafts and slidably mounted on said rods, and pounders carried by said pounder shafts.

2. In a washing machine, the combination with a tub provided with a cover, of a revolute cranked shaft mounted on the tub, a cranked shaft mounted on the cover, a link connecting said shafts together to impart a 105 vertical oscillatory movement to the shaft on the cover during the continuous rotation of the driven shaft, a member secured to the cover cranked shaft and having hollow ends, plungers slidably mounted within the hollow 110 ends of said member, pounder shafts vertically slidably mounted in the cover and provided with pounders, vertical guide posts mounted on the cover, and guide members secured to said pounder shafts and slidably 115 mounted on said guide posts and pivotally connected to said plungers.

In testimony whereof I affix my signature in presence of two witnesses.

JOHN G. SEELIG.
